UNITED STATES PATENT OFFICE.

ABRAM MARGADANT, OF MINNEAPOLIS, MINNESOTA.

PUMP-CRANK.

No. 853,707.

Specification of Letters Patent.

Patented May 14, 1907.

Application filed May 31, 1905. Serial No. 263,106.

To all whom it may concern:

Be it known that I, ABRAM MARGADANT, a citizen of the United States, residing at Minneapolis, Hennepin county, Minnesota, have 5 invented certain new and useful Improvements in Pump-Crank, of which the following is a specification.

The object of my invention is to provide for a continuous and full flow of water through 10 the pump, the velocity of the flow being such that the water will not perceptibly decrease in volume on the down stroke of the plunger.

My invention consists generally in various constructions and combinations, all as hereinafter described and particularly pointed out in the claims.

In the accompanying drawings forming part of this specification, Figure 1 is a side elevation of the upper portion of a pump standard with my invention mounted thereon. Fig. 2 is a rear view of the same. Fig. 3 is a detail view illustrating a modified construction. Fig. 4 is a detail view illustrating the antifriction guides for the plunger rod. Fig. 25 5 is a detail sectional view showing a method of applying power to the device.

In the drawing, 1 represents a suitable frame mounted upon the upper end of the ordinary pump standard, 2 the collar for a 30 compound drive attachment, and 3 bearings wherein a shaft 4 is mounted. A hand wheel 5 is mounted on the shaft 4 and provided with a suitable counterbalance 5' located, as shown in Fig. 2, between the spokes of the 35 wheel. A crank disk 6 is mounted on the inner end of the shaft 4, and provided with a crank pin 7 having an antifriction roller 8. A block 9 is secured on a plunger rod 10 which is vertically slideable between antifriction guide rollers 11 provided on an overhanging arm of the frame 1. A spring 12 is coiled about the upper portion of the plunger 10 between the frame and an adjustable collar 13 on said plunger. The plunger is preferably flat and its lower end is pivotally connected to a coupling 14 that is mounted on the upper end of the pump rod. A transverse horizontal slot 14' is provided in the block 9 wherein the antifriction roller 8 is 50 adapted to slide when the apparatus is in use. Wooden pins 15 are preferably provided in the face of the block 9 to bear on the face of the crank disk 6 and guide the plunger.

These pins are so arranged that two of them will be in contact with the face of the disk. 55 The counterbalance is so arranged on the fly wheel 5 that its weight will aid in raising the pump rod.

In Fig. 3 I have shown a slightly modified construction for use where there is a large 60 volume of water to be raised, consisting of an arm 16 secured to the collar 2. A gear 17 is mounted on the end of the shaft 4 and meshes with a pinion 18 on a stud 19 which is secured to the arm 16 and carries the hand wheel 5 65 when the compound gear mechanism is employed the counterbalance on the hand wheel is omitted.

For a power drive, I prefer to provide the apparatus shown in Fig. 5, which consists in 70 mounting a worm wheel 20 on the shaft 4 in position to engage a worm 21 which is connected to an engine (not shown) by the coupling 22.

I claim as my invention:

1. The combination with a pump cylinder and its piston rod, of a frame mounted on said cylinder, a shaft journaled in said frame and provided with a wheel having a counterbalance integrally formed thereon, a crank 80 disk secured on said shaft, a crank pin mounted in said disk, a plunger rod connected with the upper end of said piston rod, a guide therefor, a block secured on said plunger rod and having a transverse slot to receive said 85 crank pin, pins mounted in the face of said block and adapted to contact with the face of said disk in the rotation of the latter, a spring mounted on said plunger rod and put under tension by the depression of said pump 90 rod to aid said counterbalance in raising the rod on the up stroke of the pump, and an adjustable collar on said plunger rod for regulating the tension of said spring, the weight on the wheel being so located thereon as to be 95 raised as the spring is compressed and to contact with the spring in raising the pump rod substantially as described.

2. The combination with a pump cylinder and its piston rod, of a frame mounted on said cylinder, a shaft journaled in said frame and provided with a wheel, a crank disk mounted on said shaft, a crank pin carried by said disk, a plunger rod connected with the upper end of said piston rod, a guide 105 therefor, a block secured to said plunger rod

and having a horizontal slot to receive said crank pin, pins mounted in the face of said block and adapted to contact with the face of said disk during the operation of the pump, 5 and a spring mounted on said plunger rod and put under tension by the depression of said rod to aid in raising it on the up stroke of the pump, substantially as described.

In testimony whereof I have signed my name to this specification in the presence of two subscribing witnesses.

ABRAM MARGADANT.
